SNUBBER

David M. Light, Chicago, Ill., assignor to American Steel Foundries, Chicago, Ill., a corporation of New Jersey

Application December 28, 1939, Serial No. 311,234

28 Claims.

(Cl. 267—9)

My invention relates to friction absorbing devices and more particularly to a snubbing device which may be used inside a coil truck spring of a type in general use.

An object of my invention is to provide a friction absorbing device which may be used inside a coil truck spring and which may interlock with the outer coils of the spring to maintain the device in assembled relationship and to eliminate the necessity of using end plates.

Another object of my invention is to provide a friction absorbing device having lugs which interlock with the outer coils of a coil spring and which may be rotated to provide adjustment for variations in the ends of the coil spring.

Referring to the drawings,

Figure 1 is a side elevation of my novel friction absorbing device, one-half being shown in section, said section being taken substantially in the vertical plane indicated by the line 1—1 of Figure 2;

Figure 2 is a top plan view of the device shown in Figure 1;

Figure 3 is a bottom plan view of the device shown in Figure 1;

Figure 4 is a sectional view of my novel device without the coil spring, the section being taken substantially in the vertical plane indicated by the line 4—4 of Figure 5;

Figure 5 is a top plan view of my device as shown in Figure 4;

Figure 6 is a sectional view taken substantially in the horizontal plane indicated by the line 6—6 of Figure 4;

Figure 7 is a fragmentary side elevation showing the upper right lug indicated in Figure 4 and viewed from the right thereof as indicated by the line 7—7 of Figure 5;

Figure 8 is a fragmentary side elevation showing the upper left lug as seen in Figure 4, said lug being viewed from the left thereof as indicated by the line 8—8 of Figure 5;

Figure 9 is a fragmentary side elevation showing the lower left lug as seen in Figure 4, said lug being viewed from the left thereof as indicated by the line 9—9 of Figure 6; and

Figure 10 is a fragmentary side elevation showing the lower right lug as seen in Figure 4, said lug being viewed from the right thereof as indicated by the line 10—10 of Figure 6.

Describing my novel invention in greater detail, the coil spring 2 may enclose my novel snubbing device generally indicated at 4. A circular base 6 may be formed from two similar semicircular members 8, 8 and may have cen-

trally formed on its upper surface the shallow annular recess 10 serving as positioning means for a rubber spring 12. A larger circular recess 14 formed in the bottom surface of said base 6 affords positioning means for said device on a spring seat (not shown) in a well-known manner. The cylindrical housing 16 comprises two semi-cylindrical walls 18 and 20 welded as at 22 to the bottom outer annular edges of each of said members 8, 8. This construction permits said housing to spread outwardly in such manner that the outer surfaces 24 and 26 of the walls 18 and 20 respectively bear against the inner circumferential surfaces 28 of the coil spring as at 30.

As best seen from a consideration of Figures 4, 6, 9, and 10, lugs 32 and 34 project outwardly from the walls 18 and 20 respectively, said lug 32 being formed at the bottom edge of wall 18, and lug 34 being formed at a height above the bottom edge of wall 20 equal to substantially a half turn of the coil spring 2. Said lugs 32 and 34 may be formed as by pressing outwardly a section of the walls 18 and 20 in such manner as to form thereon upwardly curved surfaces 36 and 38, each with a radius substantially equal to the bar radius of the coil spring and being spirally formed along the outer circumference of said walls as at 40 and 42 to conform with the coil turns in said spring. The curved surfaces 36 and 38 of said lugs may have bearing against the inner circumferential surfaces 44 of the lower coils of said spring as at 46.

Received within said housing may be a plurality of arcuately shaped friction shoes 48, 48 having their outer faces 50, 50 in sliding frictional engagement with the inner cylindrical surfaces 52, 52 of said housing as at 54. Said shoes may be supported from a top follower 56 of circular shape having an annular flange 58 depending therefrom by a neck-like portion 60 and forming with said follower an annular slot 62 in which may be inserted the inwardly directed flanges 64, 64 formed at the top end of said shoes. 45 When under load said shoes are forced downwardly as by abutment of said flanges 64, 64 with said follower as at 66 and as the load is decreased, they may move upwardly as by abutment as at 68 with said annular flange 58.

The rubber spring 12 is of circular cross-section having its top in abutment as at 70 against the bottom face of flange 58 and its upper circumferential areas 72, 72 in abutment against the inner surfaces 14, 14 of said shoes. Said spring tapers downwardly as at 75 and is posi-

tioned on the base 6 by means of a boss 18 formed on its bottom face which is received in said recess 10.

Adjacent the top of said follower 58 on its outer circumference may be formed the lug 18 and substantially diametrically opposite may be formed the lug 80 spaced downwardly from the top of said follower a distance equal to substantially a half turn of the spring coils. Said lugs 18 and 80 may be best seen from a consideration of Figures 4, 5, 7, and 8 and have downwardly curved surfaces 82 and 84 of approximately the same radius as the bar stock of the coil spring. Said surfaces are spirally formed along the outer circumference of said follower as at 15 86 and 88 to conform to the spring coils and to afford uniform bearing against the inner circumferential areas 86 of the upper coils of said spring. The opening 92 in the upper surface of said follower affords positioning means for said device.

To assemble my novel device, the walls 16 and 20 with a member 5 welded to each may be inserted within the spring 2 in such manner that the lugs 82 and 84 may engage with a lower coil of the spring 2. The top follower 58, the friction shoes 48, 46, and the rubber spring 12 may be assembled and inserted within the housing 16 in the coil spring. The end of the top coil 94 of the spring may then be pried upwardly to permit the insertion of the lug 80 after which said top follower may be rotated until the lugs 80 and 18 are in their proper positions against the upper coils. The interlocking of said lugs with the coil spring serves to maintain my novel snubbing device in assembled relationship within the spring permitting it to be handled as a unit. By relative rotation of the top follower and housing within the coil spring, my novel device may be adjusted to variations in the position of the ends of the coil spring.

In operation as load is applied, the top follower moves downwardly forcing the friction shoes 48, 46, downwardly and compressing the rubber spring 12. As the spring 12 is compressed 45 between the top follower and the base, the rubber flows radially outward and urges the friction shoes into frictional engagement against the inner faces of the housing 16. As the load is relieved, the coil and snubbing device return to their normal positions.

It should be noted that abutment of the upper circumferential areas 12, 14 against the inner surfaces 10, 14 of said shoes serves to prevent slippage and abrasion of the rubber spring during operation. It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

Claims: 1. In a friction absorbing device, a coil spring, end followers received within said spring, one of said followers comprising semi-cylindrical members to facilitate assembly of said device, each of said members having friction surfaces received in said spring, friction shoes carried by the other of said followers, a resilient member in compression between said followers and said shoes and urging said shoes into frictional engagement with said surfaces, and means on said followers inter-

locking with spirals of said spring to maintain said device in assembled relationship.

2. In a friction absorbing device, a coil spring, end followers received within said spring, one of said followers having cylindrical friction walls received in said spring, resilient means compressed between said followers, shoes supported from the other of said followers and urged into frictional engagement with said walls by said resilient means, and spirally formed lugs on said followers projecting between coils of said spring permitting relative rotative movement of said followers and said spring whereby adjustment is provided for said followers within said spring.

3. In a friction absorbing device, a coil spring, a top follower, a bottom follower comprising semi-cylindrical segments to facilitate assembly of said device, each of said segments having friction surfaces received in said spring, friction 20 shoes carried by said top follower, a resilient member compressed between said followers and urging said shoes into frictional engagement with said surfaces, and spirally formed lugs on said followers extending between coils of said spring affording adjustment of said followers within said spring.

4. In a friction absorbing device, a coil spring, a top follower, a bottom follower comprising arcuate members, each of said members having arcuate inner and outer friction surfaces received in said spring, friction shoes carried by one of said followers, and a resilient member abutting said followers and said shoes, said member urging said shoes into frictional engagement with said inner friction surfaces and urging said outer friction surfaces into engagement with said spring.

5. In a friction absorbing device, a coil spring, a top follower, a bottom follower comprising a plurality of segments whereby assembly of said device is facilitated, each of said segments having friction surfaces received in said spring, friction shoes supported from said top follower and having engagement with said surfaces, and a resilient member in compression between said followers and said shoes, said member having non-sliding abutment with said shoes to prevent abrasion of said member.

6. In a friction absorbing device, a coil spring, a top follower, a bottom follower having friction surfaces received in said spring, resilient means compressed between said followers, shoes supported from said top follower and urged into frictional engagement with said surfaces by said resilient means, and means maintaining said device in assembled relationship, said means comprising spirally formed lugs on said followers projecting between coils of said spring.

7. In a friction absorbing device, inner and outer resilient means, end followers received within said outer resilient means and compressing said inner resilient means therebetween, shoes supported from one of said followers and having complementary arcuate engaging surfaces with the other of said followers, and means on said followers interlocking with said outer resilient means to maintain said device in assembled relationship.

8. In a friction absorbing device, a coil spring, a top follower, a bottom follower having cylindrical walls received within said spring, a plurality of friction shoes supported from one of said followers, and a tapered resilient member compressed between said followers and urging

- 5 said shoes into frictional engagement with said walls, and means on said followers interlocking with spirals of said spring to maintain said device in assembled relationship.
9. In a friction absorbing device, a coil spring, a top follower, a bottom follower having friction surfaces received in said spring, a resilient member compressed between said followers, shoes supported from said top follower and urged into frictional engagement with said surfaces by said member, and means maintaining said device in assembled relationship, said means comprising lugs on said followers interlocking with coils of said spring.
10. In a friction absorbing device, a coil spring, a top follower, a bottom follower having friction surfaces received in said spring, a resilient member compressed between said followers, shoes supported from said top follower and urged into frictional engagement with said surfaces by said member, and means maintaining said device in assembled relationship, said means including lugs projecting between spirals of said spring.
11. In a friction absorbing device, a coil spring, a top follower, a bottom follower having friction surfaces received in said spring, resilient means compressed between said followers, shoes supported from said top follower and urged into frictional engagement with said surfaces by said resilient means, and means on said followers interlocking with coils of said spring whereby said device is maintained in assembled relationship.
12. In a friction absorbing device, a coil spring, top and bottom followers, one of said followers having cylindrical friction walls received within said spring, a resilient member in compression between said followers, friction shoes supported from the other of said followers and extending between said member and said walls, and lugs on each of said followers engaging spirals of said spring whereby said device is maintained in assembled relationship.
13. In a friction absorbing device, a coil spring, end followers received within said spring, one of said followers comprising a plurality of arcuate segments to facilitate assembly of said device, each of said segments having friction surfaces received within said spring, shoes supported from the other of said followers and having frictional engagement with said surfaces, and a resilient member abutting said followers and said shoes.
14. In a friction absorbing device, a coil spring, end followers, one of said followers having cylindrical friction walls received in said spring, a resilient member compressed between said followers, shoes supported from the other of said followers and urged into frictional engagement with said walls by said member, and means on said followers affording adjustment of said followers within said spring.
15. In a friction absorbing device, a coil spring, a bottom follower having friction walls received in said spring, a top follower, resilient means compressed between said top and bottom followers, shoes urged into frictional engagement with said walls by said member, and lugs on said followers interlocking with coils of said spring to maintain said device in assembled relationship.
16. In a friction absorbing device, inner and outer resilient means, end followers received with in said outer resilient means in interlocking engagement therewith and abutting said inner resilient means, and shoes supported from one of said followers and urged into frictional engage- 70
- 5 ment with the other of said followers by said inner resilient means.
17. In a friction absorbing device, a coil spring, a top follower, a bottom follower having cylindrical friction walls received within said spring, friction shoes supported from one of said followers and having frictional engagement with said walls, and resilient means in compression between said followers, said resilient means having non-sliding abutment with said shoes to prevent abrasion.
- 15 18. In a friction absorbing device, a coil spring, end followers received within said spring, one of said followers having friction walls received in said spring, a plurality of friction shoes having frictional engagement with said walls and carried by the other of said followers, and a resilient member abutting said followers and said shoes.
19. In a friction absorbing device, a coil spring, a top follower, a bottom follower comprising a plurality of segments, each of said segments having friction surfaces received in said spring, friction shoes carried by one of said followers, and resilient means abutting said shoes and said followers and urging said shoes into frictional engagement with said surfaces.
- 20 20. In a friction absorbing device, a coil spring, a bottom follower having friction surfaces received in said spring, a top follower, friction shoes 30 carried by said top follower and having frictional engagement with said surfaces, and resilient means abutting said top and bottom followers and said shoes.
- 35 21. In a friction absorbing device, end followers, a plurality of resilient members, friction shoes supported from one of said followers, and friction walls on the other of said followers engaging said shoes and one of said resilient members, the other resilient member having abutment with said followers and said shoes.
- 40 22. In a friction absorbing device, a coil spring, a top follower supporting segmental friction shoes, a segmental bottom follower having friction walls projecting between said spring and said shoes for frictional engagement therewith, and a resilient member abutting said shoes and said followers.
- 45 23. In a friction absorbing device, a coil spring, a top follower supporting segmental friction shoes, a segmental bottom follower having friction walls projecting between said spring and said shoes for frictional engagement therewith, a resilient member compressed between said shoes and said followers, and means on said followers engaging said spring to retain said device in assembly.
- 50 24. In a friction absorbing device, outer resilient means, a segmental bottom follower, a top follower, friction shoes supported from said top follower, and a resilient member abutting said shoes and said followers for bringing said shoes, said bottom follower, and said outer resilient means into tight frictional engagement.
- 55 25. In a friction absorbing device, a coil spring, a top follower, friction shoes supported from said top follower, a bottom follower with friction walls having cylindrical face engagement with said shoes and said spring, and a resilient member abutting said shoes and said followers.
- 60 26. In a friction absorbing device, a coil spring, a top follower, friction shoes supported from said top follower, a bottom follower with friction walls having cylindrical face engagement with said shoes and said spring, and means on said followers interlocking with said spring.

27. In a friction absorbing device, a coil spring, end followers received within said spring and having spiral interlocking engagement therewith, shoes supported from one of said followers, and friction walls on the other of said followers, and a resilient member abutting said shoes and said followers and urging said shoes into tight frictional engagement with said walls when compressed.

28. In a friction device, inner and outer resilient members, end followers interlocked with said outer resilient member and abutting said inner resilient member, and friction members associated with said end followers, each of said members having cylindrical face engagement with the adjacent member along the axis of said device.

DAVID M. LIGHT.
